(57) **CLAIM**

The ornamental design for a connector for musical instrument cable, as shown and described.

DESCRIPTION

FIG. 1 is a perspective view of a connector for musical instrument cable showing our new design;
FIG. 2 is a right side elevation view thereof;
FIG. 3 is a left side elevation view thereof;
FIG. 4 is a front elevation view thereof;
FIG. 5 is a rear elevation view thereof;
FIG. 6 is a top plan view thereof; and,
FIG. 7 is a bottom plan view thereof.

In FIGS. 1-7, the broken lines represent environmental subject matter and form no part of the claimed design.
